UNITED STATES PATENT OFFICE.

HENRY A. HILLS, OF GRAND RAPIDS, MICHIGAN.

SAFETY DEVICE FOR ELECTRICALLY-HEATED IMPLEMENTS.

1,008,411.

Specification of Letters Patent. Patented Nov. 14, 1911.

Application filed November 9, 1908. Serial No. 461,613.

To all whom it may concern:

Be it known that I, HENRY A. HILLS, of Grand Rapids, county of Kent, and State of Michigan, have invented a certain new and useful Safety Device for Electrically-Heated Implements, of which the following is a description.

My invention relates to means for controlling the electric circuit to an electrically heated implement to prevent overheating the same.

The object of my invention is to provide a simple, convenient and reliable device of the kind described whereby the electric circuit is interrupted when the implement heated by the circuit reaches a predetermined temperature.

To this end my invention consists in the novel construction, arrangement and combination of parts herein shown and described and more particularly pointed out in the claims.

In the accompanying drawings wherein like or similar reference characters indicate like or corresponding parts; Figure 1, is a longitudinal section taken substantially on line 1—1 of Fig. 2 showing one form of my improvement applied to an electrically heated flat iron. Fig. 2, is a section taken substantially on line 2—2 of Fig. 1, with the flat iron shown in elevation. Fig. 3, is a sectional elevation of my device applied to a stand or holder for a flat iron.

In the preferred form shown in the drawings, 1 is a flat iron equipped in substantially the usual manner for heating the same by means of an electric current.

2 and 3 are binding posts for attaching the conductors to the element, all formed and arranged in the usual or any preferred manner.

A fuse block 4, preferably formed of porcelain or other refractory non-conducting material is attached to the element 1 by suitable screws or bolts 5—5 or other convenient means for holding the same securely in position upon the element.

In the preferred form shown the block 4 is provided with a recess 6, opening toward the wall of the element to which it is at-

tached. Suitable binding posts 7—7 are provided for attaching the electric conductors to the block. As shown the binding posts 7 are each provided with a stem 8, extending through the outer wall of the block. Each of the stems 8 is provided with a clamp 10 or other suitable means positioned within the recess 6 for engaging a fusible connection 9 to electrically connect the binding posts 7—7. The several parts are preferably so formed that a portion of the fusible connection 9 is brought into close proximity with the wall of the element 1 so that when the temperature of the element reaches a certain predetermined limit a portion of the fusible member will be melted, thus breaking the electric circuit to the element.

Any suitable means may be provided to insure the above described operation. In the form shown the stems 8—8 are positioned at the opposite ends of the chamber 6 and are each provided with a spring clamp 10 within the chamber arranged to engage the extremity of the fusible member. A bridge or wall 11 is positioned transversely of the chamber between the clamps so that the central portion of a fuse engaged in the clamps will be held by the wall 11 close to the element. If desired suitable pins or posts 12—12 may be provided at opposite sides of the wall 11, as shown to hold the fuse snugly against the outer face of the wall and control its position in the chamber. An opening 14 may be provided in the lower wall of the fuse-block so that in case the fuse is melted the melted metal may freely escape from the chamber.

In operation one of the binding posts 7 is connected by means of a conductor 15 to one of the binding posts as the post 3 upon the element, the opposite binding post 7 and the binding post 2 upon the element are connected respectively to the conductors 16 and 17 suitably arranged to connect the element to the source of electric energy. When thus arranged it is evident that in case the fusible member 9 is melted the connection between the conductors 16 and 15 will be broken thus breaking the electric

circuit to the element and effectually preventing any overheating of the same.

In the form shown in Fig. 3, my improvement is attached to a stand or holder 18 adapted to receive and support the element when not in use. In this form my improvement is so positioned that when the element is placed upon the stand a part of the fusible member 19 between the clamps 10-10 10 will be brought in close proximity to a face of the element substantially as above described. The general operation and construction being also substantially the same as herein before set forth.

Having thus described my improvement, it is obvious that various immaterial modifications may be made in my device without departing from the spirit of my invention, hence I do not wish to be understood as 20 limiting myself to the exact form of construction shown.

What I claim as new and desire to secure by Letters Patent is:

1. A device of the kind described, comprising an insulating block provided with means for attaching electric conductors thereto and means for securing a fusible member between said conductors, in combination with means adapted to engage the 30 central portion of said fusible member to hold the same in a fixed position.

2. A device of the kind described, comprising an insulating block provided with means for attaching electric conductors thereto, and means for securing a fusible member between said conductors, in combination with means upon said block adapted to engage the central portion of said fusible member to hold the same in a fixed position.

40 3. A device of the kind described, comprising an insulating block provided with means for connecting a fusible member in an electric circuit, means for securing said insulating block in position, an element heated by the current passing through said fusible member and means for temporarily supporting said element in close proximity to a portion of said fusible member.

4. A device of the kind described, comprising an insulating block provided with a recess in its face and engaging means positioned in said recess near the ends thereof for connecting a fusible member in an electric circuit, in combination with means arranged in said recess adapted to position a portion of said fusible member in close proximity to the face of said insulating block.

5. A device of the kind described, comprising an insulating block provided with a recess in its face and engaging means positioned near the ends of said recess adapted to connect a fusible member in an electric circuit, in combination with means extend-

ing transversely of said recess adapted to 65 support a portion of said fusible member in close proximity to the face of said block.

6. A device of the kind described, comprising an insulating block provided with a recess in its face and engaging means positioned in said recess near the ends thereof adapted to connect a fusible member in an electric circuit, in combination with supporting means extending transversely of 70 said recess adapted to position a portion of 75 said member in close proximity to the face of said block and means positioned at opposite sides of said supporting means arranged to space the remaining portion of said fusible member from the face of said block. 80

7. A device of the kind described, comprising an insulating block provided with a recess in its face and engaging means positioned in said recess near the ends thereof adapted to connect a fusible member in an 85 electric circuit, in combination with means formed integrally with said block extending transversely of said recess adapted to position a portion of said fusible member in close proximity to the face of said block. 90

8. A device of the kind described, comprising an insulating block provided with a recess in the face and engaging means positioned in said recess near the ends thereof adapted to connect a fusible member in an 95 electric circuit, in combination with means arranged in said recess to position a portion of said fusible member in close proximity to the face of said insulating block and means for securing said block in position and thereby control the distance between said fusible member and an element heated by the electric circuit passing through said fusible member. 100

9. A device of the kind described, comprising an insulating block provided with a recess in its face, and engaging means positioned in said recess near the ends thereof adapted to connect a fusible member in an electric circuit, in combination with means arranged in said recess adapted to position a portion of said member in close proximity to the face of said block, a stand adapted to support a heated implement and means for attaching said insulating block to said stand with its face in close proximity to the face of said stand. 110

10. A device of the kind described, comprising an insulating block provided with means for attaching electric conductors 120 thereto and means for securing a fusible member between said conductors, in combination with means formed integral with said block adapted to engage the central portion of said fusible member to hold the 125 same in a fixed position.

11. A movable element, means for heating said element, and a stand for tem-

porarily supporting said element, in combination with a fusible member mounted upon said stand with a part arranged to be heated by said element when the same is upon said stand, and adapted to prevent the overheating of the element.

In testimony whereof, I have hereunto

signed my name in the presence of two (2) subscribing witnesses.

HENRY A. HILLS.
